UNITED STATES PATENT OFFICE.

KARL PETERSON, OF JAMESTOWN, NEW YORK.

DESIGN FOR A MEMBER OF A PAIR OF PLIERS, CUTTERS, AND SIMILAR ARTICLES.

47,389.

Specification for Design.

Patented May 25, 1915.

Application filed January 18, 1915. Serial No. 2,985. Term of patent 14 years.

To all whom it may concern:

Be it known that I, KARL PETERSON, a citizen of the United States, residing at the city of Jamestown, in the county of Chautauqua and State of New York, have invented a Design for a Member of a Pair of Pliers, Cutters, and Similar Articles, of which the following, taken in connection with the accompanying drawings, is a specification.

Figure 1 is an edgewise view of a member of a pair of pliers showing my new design, and Fig. 2 is a plan view of the handle of

the pliers taken at right angles to the view shown in Fig. 1 showing the design in detail.

I claim as new:

The ornamental design for a member of a pair of pliers, cutters and similar articles, as shown.

In testimony whereof I have affixed my signature in the presence of two witnesses.

KARL PETERSON.
